UNITED STATES PATENT OFFICE.

OSWALD S. PULLIAM, OF ST. LOUIS, MISSOURI.

DRAFT-RIGGING CARRIER.

SPECIFICATION forming part of Letters Patent No. 777,539, dated December 13, 1904.
Application filed September 2, 1904. Serial No. 223,075. (No model.)

To all whom it may concern:

Be it known that I, OSWALD S. PULLIAM, a citizen of the United States, residing in the city of St. Louis, in the State of Missouri, have invented certain new and useful Improvements in Draft-Rigging Carriers, of which the following is a full, clear, and exact description, reference being had to the accompanying drawings, forming part of this specification.

10 My invention relates to a draft-rigging carrier for attachment to car-sills so constructed as to provide at its under side a center-bearing integral with the carrier for the car-truck bolster.

15 It also relates to means whereby the draft-rigging carrier is united with the body-bolster, the object being to throw a part of the strain usually exerted upon the draft-rigging carrier upon the body-bolster.

20 Figure I is a top or plan view of my draft-rigging carrier and a body-bolster set thereinto. Fig. II is a vertical longitudinal section taken on line II II, Fig. I, showing the center-bearing cast integrally with the carrier. Fig. III is a vertical cross-section taken on line III III, Fig. I. Fig. IV is a horizontal section taken on line IV IV, Fig. II. Fig. V is a perspective view of the central portion of the body-bolster. Fig. VI is a perspective 25 view of the bolster-receiving portion of the draft-rigging carrier.

1 designates my cast-metal draft-rigging carrier proper, which is designed to be mounted upon the center sills of a railway-car, to 30 which it is secured by bolts passed vertically through the sills and through ears 2, projecting laterally at the sides of the carrier proper.

The end A of the carrier proper receives the draft-rigging, which may be mounted 35 therein in any suitable manner, the mounting of the rigging constituting no part of my invention. In the top side of the carrier proper and extending transversely thereacross is a body-bolster recess 3, that contains ledges 4.

40 At the sides of the carrier and at or near the bottom thereof, as seen in Figs. III and VI, are ears 5. At the lower side of the carrier and integral therewith is a center-bearing 45 6 for the truck-bolster, that occupies a position immediately beneath the body-bolster, seated in the recess 3.

7 designates a body-bolster that has upper and lower chords 8 and 9 and an intervening vertical web 10. The lower chord and web of this body-bolster are cut away at the longitudinal center of the bolster, as seen at 11, Fig. V, to permit of the bolster being seated in the recess 3 of the draft-rigging carrier, with its center-bearing 12 resting at the bottom of said recess and on the ledges 4, as seen in Figs. II and III. Projecting laterally, respectively, from the upper chord 8 and lower chord 9 are ears 13 and 14, corresponding in position to the positions of the ears 5 of the draft-rigging carrier. The bolster-ears 14 are designed to rest upon the carrier-ears 5, as seen in Fig. III, and the ears 5, 13, and 14 receive combinedly bolts passed vertically therethrough, whereby the body-bolster is held to the draft-rigging carrier.

70 By the construction of draft-rigging carrier and bolster as herein described I render the carrier and bolster practically a unit, due to the connection between them, thereby securing greater rigidity between said parts, and 75 by producing the truck-bolster center-bearing as an integral member with the draft-rigging carrier I furnish a construction in which greater strength of the parts is obtained and wherein there is no liability of the center-bearing to become loosened and displaced, as is liable to occur where it is made separate from the part by which it is carried, as has heretofore been the custom.

I claim as my invention—

1. As a new article of manufacture, a cast-metal draft-rigging carrier having a truck-bolster center-bearing cast integral therewith, substantially as set forth.

2. The combination of a draft-rigging carrier proper provided with a transversely-extending recess, a body-bolster seated in said recess, and means whereby said body-bolster is secured to said draft-rigging carrier; said carrier and bolster being provided with bolt-receiving ears located in proximity to the recess in said carrier, substantially as set forth.

OSWALD S. PULLIAM.

In presence of—

E. S. KNIGHT,
NELLIE V. ALEXANDER.
